(57) **CLAIM**

I claim the ornamental design for a fastener for a conveyor belt, as shown and described.

DESCRIPTION

FIG. 1 is a front perspective view of a fastener for a conveyor belt, showing my new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a front elevational view thereof;
FIG. 7 is a rear elevational view thereof; and,
FIG. 8 is a rear perspective view thereof showing the fastener for a conveyor belt interconnected with another fastener by a wire.

The broken lines in the drawings illustrate portions of the Fastener for a conveyor belt and form no part of the claimed design. The dot-dash-dot broken lines in the drawings define the bounds of the claimed design and form no part thereof.
